UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Application filed May 31, 1921. Serial No. 473,686.

To all whom it may concern:

Be it known that I, FRED N. LA CHAPELLE, a citizen of the United States, residing at Beverly, in the county of Essex and State 5 of Massachusetts, have invented certain Improvements in Lasting Machines, of which the following description, in connection with the accompanying drawings, is a specification, like reference characters on the drawings indicating like parts in the several figures.

This invention relates to machines for lasting successive portions of the upper of a shoe progressively about the periphery 15 of the shoe.

For the purpose of illustration and exemplification the invention is herein shown as embodied in a machine of the type disclosed in United States Letters Patent 20 1,185,108 granted May 30, 1916, on my application, and known as a "thread fastening machine." In the operation of this machine as previously organized an upper, already lasted and secured by tacks, is fastened by 25 a thread fastening to the lip or rib of an innersole. The lasting tacks may then be withdrawn and the upper sewed to the lip, rib or between-substance, and since there are then no metallic fastenings in the portion 30 of the shoe treated there is no danger of the needle striking such fastenings and being deflected or broken.

One object of the present invention is to enable machines of this type to be used 35 for lasting shoes in the first instance, the utility of the machine for its prior purpose not necessarily being affected.

Another object of the invention is to provide an improved machine by which the 40 upper may be lasted and secured in lasted position by fastenings which may remain in the shoe without unfavorably affecting the operations of machines used subsequently in the manufacture of the shoe.

A still further object of the invention 45 is to provide lasting mechanism which may be used to advantage both with means for securing the upper and also in operations where the upper is secured by cement, as 50 for example, in rubber shoe work.

A feature of the invention consists in a lasting element operated to engage the side 55 of a shoe upheld to positioning means by the hands of the operator, and acting to wipe the upper at the side of the shoe toward

the shoe bottom. The lasting element preferably has a friction face for engaging the upper and is given a movement heightwise of the last in conjunction with movement inwardly of the last, said movements occurring in 60 each cycle of the machine to work into lasted position a selected portion of the upper. As herein shown the lasting element comprises a flexible strap held under spring tension applied at its lower end and supported so that 65 its operating portion is inclined upwardly and inwardly with relation to a shoe presented bottom up to the shoe positioning means. The supporting means or strap is arranged for automatic movement toward 70 the shoe once in each cycle of the machine in a plane substantially parallel to the last bottom and is yieldingly held from free upward movement, for instance by the spring tension on the belt referred to above. The 75 portion of the supporting means which carries, and is preferably covered by, the upper end of the strap, in its movement toward the shoe, engages the side of the shoe well below the plane of the sole, and because of 80 the inclined position of the strap a vertical component of the inward pressure lifts the strap while in contact with the upper, thus producing an inward and upward yielding 85 wiping action on the portion of the upper being lasted. The upwiping action of the lasting element is also assisted and enhanced by the inward inclination of the portion of the last engaged by its upper end which inclination is especially pronounced at the 90 shank on the inner side of the shoe where side lasting is most difficult.

Another feature of the invention consists in an organization comprising means for securing an upper to an innersole by successive operations of the securing means, and means for upwiping the upper toward the last bottom and into lasted position prior to each securing operation. Preferably the securing means comprises, as shown, means 95 for inserting individual non-metallic fastenings through the upper and innersole in a direction substantially parallel to the last bottom, and the lasting means comprises 100 a friction lasting element acting to conform 105 the upper intimately to the contour of the last and to work the upper toward the point where it is to be secured.

Preferably the operations of the securing means and the lasting element occur in 110

timed relation in each cycle of the machine which is organized to stop automatically after the completion of the cycle, the machine being under the control of the operator through a suitable treadle. The operation of the lasting means, therefore, as well as that of the securing means, is under control at the will of the operator.

- As another feature of the invention the lasting means is organized to hold the upper positively against the upper corner of the edge face of the innersole and the upper is pressed into the angle between the rib and feather of the innersole, for example, by a back gage, and is thereby held in position to receive fastenings inserted through the upper and innersole rib parallel to the last bottom.
- These and other features of the invention will appear more fully from the following description when read in connection with the accompanying drawing and will be pointed out in the appended claims.

In the drawing, Fig. 1 is a side view of a lasting machine embodying the present invention, and

Fig. 2 is a detail showing the position of the lasting and securing means while they are in operative relation to the work.

In Fig. 1 of the drawing is shown the head of a thread fastening mechanism constructed in accordance with my prior patent above referred to, this mechanism constituting a convenient and effective form of the means of the present invention for securing or fastening the upper. For a fuller description of this mechanism than is herein given reference may be had to my prior patent above mentioned.

The machine comprises a column 2 on which is secured the frame 6 of the machine head in which is journaled a cam shaft 8 carrying a series of cams from which the various operating mechanisms with which the machine is provided are operated.

The lasting mechanism comprises a supporting slide 12 pivoted at its rear end to an arm 14 secured to a rockshaft 16 which has an arm 18 carrying a cam roll 20. The cam roll engages a suitable cam on the cam shaft 8 contoured to rock the shaft 16 at the proper time in the cycle of the machine to cause the slide 12 to move toward the shoe. The forward portion of the slide normally rests in sliding engagement with the upper end of a plate 22 secured at 24 to the machine frame. The slide 12, forwardly of the plate 22, is forked, one branch 26 extending substantially horizontally and the other branch 28 extending downwardly with its end located rearwardly of the end of the branch 26. A strap 30, which constitutes the element of the lasting mechanism which engages the upper of the shoe, passes through an opening in the lower branch 28,

upwardly outside of the branch 26, downwardly through an opening in its end and through the opening in the lower branch 28. The two ends of the strap 30 are perforated to receive one end of a spring 32 the other end of which is secured to a downward extension of the plate 22, the strap being thereby held under suitable tension during movement of the slide 12 to effect the lasting operation.

The work positioning means against which the shoe is upheld in the hands of the operator is provided by a channel guide 34. The channel guide preferably has two feet spaced lengthwise of the shoe sufficient to enable the thread fastening to be formed between them, the feet engaging the inner face of the rib and assisting the operator to hold and position the shoe during the operation of the lasting and securing mechanisms.

For the lasting operation, the operator holds the shoe in the position shown in Fig. 1 to last, for instance, the inner side of the shoe. He then depresses the treadle to start the machine. The slide 12 is advanced toward the shoe by rotation of the cam shaft 8, causing the strap 30, held under tension by the spring 32 and in an inclined position as shown, to engage the upper well down on the side of the shoe. As the movement of the slide continues a vertical component of pressure due to the inclination of the strap, or by reason of the engagement of the end of the branch 26 with the upwardly and inwardly inclined face of the last or both, causes an upward movement of the strap while in contact with the shoe against the tension of the spring 32. This action not only lays the upper into close conformity with the contour of the last, but produces a tensioning effect heightwise of the last. The end of the branch 26 covered by the strap 30 is given sufficient positive movement toward the shoe by its cam to lay the upper against the upper corner of the edge face of the innersole as shown in Fig. 2. To hold the margin of the lasted upper beyond the lasting element in position to be fastened mechanism is provided

comprising a back gage 36 mounted on a bar 38 extending parallel to the slide 12. The bar is supported on parallel links 40, 42 and is urged forwardly by a tension spring 44 connected between the machine frame and the bar 38. Movement of the bar 38 under the influence of the spring 44 is controlled by a lever 46 fulcrumed on the shaft 16 and carrying a cam roll 48 engaging a cam on the cam shaft 8 and contoured to permit forward movement of the bar 38 after the upper has been operated upon by the lasting element 30. Because of the inclinations of the links 40, 42 the back gage 36 moves downwardly as well as forwardly and acts to press the margin of the lasted upper in-

to the angle between the rib and feather of the innersole in position to be secured. The portion of the upper thus worked into lasted position is secured by the thread fastening mechanism of the machine which mechanism comprises a curved eye-pointed needle 50 carrying a thread 52. The needle 50 is carried on a needle segment pivoted at 54 and connected by a link 56 to a lever 58 which in turn is operated by a bell crank lever 60 from a cam on the shaft 8, as is more fully described in my prior patent above mentioned, to cause the needle to make two stock penetrating movements in each cycle, the second movement being longer than the first. Between these movements the needle is moved laterally by mechanism operated by movement of a cam roll 61 engaging a peripheral cam path in a cam block 62. Upon its first penetrative movement the needle carries a loop of thread through the upper and innersole rib substantially parallel to the last bottom which loop is engaged by a hooked thread finger 64 which holds the loop as the needle retracts. The needle then moves laterally and again penetrates the upper and rib, carrying a second loop through the work. The hooked thread finger 64 is then operated to carry the first loop through the second loop, this operation being facilitated by the greater movement of the needle at this time. The needle is then retracted and the second loop is tightened upon the first loop to set a fastening by the action of the usual take-up lever 66. The needle operates through a slot in the back gage 36 and after the thread fastening is formed a thread cutting knife 68 is operated and cooperates with the back gage 36 to sever the thread close to the shoe, leaving the shoe free to be repositioned by the operator for another lasting and securing operation. When the cycle of operations described has been completed the parts return to the position shown in Fig. 1 and the machine stops.

Having thus described my invention, what I claim as new and desire to secure by Letters Patent of the United States is:

50 1. In a machine for progressively lasting a shoe upper, the combination of wiping lasting means for treating successive portions of the shoe upper and working them progressively into lasted position, and means for intermittently operating the lasting means to move heightwise of the shoe in rubbing engagement therewith.

60 2. In a lasting machine, the combination of a lasting element constructed and arranged to treat successive portions of a shoe upper progressively along the edge of a shoe having a surface to engage the side of an inverted shoe presented thereto in the hands of the operator, and means operative at will to cause the lasting element to en-

gage the upper and wipe it upwardly toward the shoe bottom.

3. In a lasting machine, the combination of means for positioning an inverted shoe presented to said means in the hands of the operator, a lasting element inclined to the plane of the shoe bottom, and means for operating said lasting element intermittently to cause it to approach the shoe and to upwipe and overwipe the upper.

4. In a machine of the class described, the combination of a single wiping lasting means movable heightwise and transversely of a shoe, and power means for intermittently operating the lasting means transversely to engage the side of the shoe and to move heightwise of the shoe in rubbing engagement therewith.

5. In a lasting machine, the combination of a lasting element having an inclined rubbing surface to engage the side of an inverted shoe presented thereto in the hands of the operator, and means operative at will to cause the lasting element to engage the upper at the side of the shoe and to be lifted by said inclined surface to wipe the upper upwardly toward the shoe bottom.

6. In a lasting machine, the combination of means for positioning an inverted shoe presented to said means in the hands of the operator, a flexible friction lasting element inclined to the plane of the shoe bottom, means for maintaining said element under tension, and means for operating said lasting element intermittently to cause it to approach the shoe and to upwipe and overwipe the upper.

7. In a lasting machine, the combination of a lasting element having a surface extending in a direction inclined upwardly and outwardly of the machine to engage the side of an inverted shoe presented thereto in the hands of the operator, and means operative at will to cause the lasting element to engage the upper and wipe it upwardly toward the shoe bottom.

8. A lasting machine having, in combination, a strap extending in a direction inclined upwardly and outwardly of the machine to engage the side of an inverted shoe presented thereto in the hands of the operator, and means operative at will to cause the strap to engage the upper and wipe it upwardly and inwardly over the shoe bottom.

9. A lasting machine having, in combination, a strap yieldingly held at its lower end and arranged to extend in a direction inclined upwardly and outwardly of the machine to engage the side of an inverted shoe presented thereto in the hands of the operator, and means connected with the upper end of the strap and operative at will to cause the strap to engage the upper and

wipe it upwardly toward the shoe bottom.

10. A machine of the class described having, in combination, a lasting element arranged and operated to upwipe and overwipe successive portions of an upper progressively and to come to rest, and fastening mechanism arranged to insert separate fastenings to secure the upper to the inner-sole.

11. A machine of the class described having, in combination, a lasting element arranged and operated to upwipe and over-

wipe successive portions of an upper progressively and to come to rest with the upper held in position to be fastened to the innersole rib, and fastening mechanism arranged to insert separate fastenings through the upper and upstanding rib of the inner-sole.

12. A machine of the class described having, in combination, lasting mechanism arranged to upwipe and overwipe successive portions of an upper progressively, and fastening mechanism arranged to insert separate non-metallic fastenings through the upper and upstanding rib of the innersole in a direction parallel to the shoe bottom.

13. A lasting machine having, in combination, upper fastening mechanism constructed and arranged progressively to fasten successive portions of a shoe upper in lasted position, and lasting means acting intermittently to upwipe and overwipe each successive portion of the upper against the last prior to each operation of the fastening mechanism.

14. A lasting machine having, in combination, upper fastening mechanism constructed and arranged progressively to fasten successive portion of a shoe upper in lasted position, and a lasting element acting intermittently to upwipe against the last each successive portion of the upper prior to each operation of the fastening mechanism.

15. A machine of the class described having, in combination, lasting mechanism comprising a lasting element constructed and arranged for intermittent operation to upwipe and overwipe against the last successive portions of an upper progressively, and fastening mechanism arranged to insert separate fastenings to secure the lasted upper to the innersole.

16. A lasting machine having, in combination, upper fastening mechanism, an upper lasting element extending upwardly along the side of an inverted shoe located in operative relation to the fastening mechanism, and means for operating the element to cause it to effect an inward and upward lasting action on the upper prior to each operation of the upper fastening mechanism.

17. A lasting machine having, in combination, upper fastening mechanism, upper stretching means extending upwardly at the

side of an inverted shoe in operative relation to the fastening mechanism, and means acting automatically to cause a single inward and upward lasting movement of said stretching means in conjunction with each operation of the upper fastening mechanism.

18. A lasting machine having, in combination, means for fastening an upper to an insole, a lasting member arranged to be brought into contact with the upper of a shoe presented to the fastening means at a point on the side of the shoe below the last bottom, and means for giving the lasting means a limited movement transversely of and heightwise of the last while in contact with the upper to effect a single upwiping and overwiping action on the upper prior to each operation of the fastening means.

19. A lasting machine having, in combination, a strap arranged to extend in a direction inclined upwardly and outwardly of the machine to engage the side of an inverted shoe presented thereto in the hands of the operator, means operative at will to cause the strap to engage the upper and wipe it upwardly and inwardly of the shoe bottom, and fastening mechanism operating in conjunction with the operation of the strap and subsequently thereto to secure the upper in lasted position.

20. A lasting machine having, in combination, means for fastening an upper to an innersole, a lasting member arranged to be brought into contact with the upper of a shoe presented to the fastening means at a point on the side of the shoe adjacent to the part to be fastened, and means for giving the lasting means intermittently a movement heightwise of the last while in contact with the upper to effect a single upwiping action on the upper prior to each operation of the fastening means.

21. A lasting machine having, in combination, friction lasting means arranged to extend in a direction inclined upwardly and outwardly of the machine to engage the side of an inverted shoe presented thereto in the hands of the operator, means operative at will to cause the lasting means to engage the upper and rub it upwardly toward the shoe bottom, and fastening mechanism operating in conjunction with the operation of the lasting means and subsequently thereto to secure the upper in lasted position.

22. A lasting machine having, in combination, means for fastening an upper to an innersole, a flexible lasting member arranged to be brought into contact with the side of the upper of a shoe presented to the fastening means at a point adjacent to the part to be fastened, said flexible means being given a movement heightwise of the last while in contact with the upper to effect a single upwiping action of the upper prior to each operation of the fastening means and having a

return movement after the upper is fastened.

23. A machine of the class described having, in combination, lasting mechanism comprising a flexible lasting element constructed and arranged for intermittent operation to upwipe and overwipe successive portions of an upper progressively, and fastening mechanism arranged to insert separate fastenings through the lasted upper and the upstanding rib of the innersole in a direction substantially parallel with the shoe bottom.

24. A lasting machine having, in combination, upper fastening mechanism, and lasting means comprising an upper rubbing strap operated to engage a side of the shoe and move heightwise of the shoe in rubbing engagement therewith prior to each operation of the fastening mechanism and to move away from the shoe after the upper is fastened.

25. A lasting machine having, in combination, upper fastening mechanism, lasting means comprising an upper rubbing strap, and means for operating the strap to move it toward the shoe and to cause it to engage a side of the shoe and move lengthwise in rubbing engagement therewith prior to each operation of the fastening mechanism.

26. A lasting machine having, in combination, upper fastening mechanism, lasting means comprising an upper rubbing strap, and means for operating the strap in timed relation to the fastening mechanism to effect an upwiping of a portion of the upper prior to each operation of the fastening mechanism.

27. A lasting machine having, in combination, upper fastening mechanism, an upper stretching strap extending upwardly toward the bottom of an inverted shoe located in operative relation to the fastening mechanism, and means for operating the strap in timed relation to the fastening mechanism to cause an inward and upward lasting action of the strap in conjunction with the operation of the upper fastening mechanism.

28. A lasting machine having, in combination, upper fastening mechanism, an upper stretching strap extending upwardly and outwardly toward the side of an inverted shoe in operative relation to the fastening mechanism, and means acting automatically to cause a single inward and upward lasting action of the strap in conjunction with each operation of the upper fastening mechanism.

29. In a machine for lasting the sides of shoes, the combination with means for securing a portion of a lasted upper to the rib of an insole, of means operated to engage the inclined portion of the side of the last adjacent to its bottom and arranged to be lifted by the cam action of said inclined

portion and to wipe the upper inwardly into position to be fastened.

30. In a machine for lasting the sides of shoes, the combination with means for securing a portion of a lasted upper to the rib of an insole, of means operating to engage the inclined portion of the side of the last adjacent to its bottom and arranged to be lifted by the cam action of said inclined portion, and flexible means forming a continuation of the shoe engaging face of said operating means acting to upwipe the side of the upper as said operating means is raised by the inclined portion of the last.

31. In a machine for lasting the sides of shoes, the combination with means for securing a portion of a lasted upper to the rib of an insole, of means operated to engage the side of the last adjacent to its bottom, and yielding means having a shoe engaging face at an inclination to the shoe bottom forming a continuation of the shoe engaging portion of said operated means, said yielding means acting to upwipe the upper at the side of the shoe during operation of said operated means.

32. In a machine for lasting the sides of shoes, the combination of means for securing a portion of a lasted upper to the rib of an insole, means operated in a direction substantially parallel to the last bottom to engage the side of the last below the shoe bottom and arranged for vertical movement while in contact therewith, a lasting element forming a continuation of the shoe engaging face of said operated means, and resilient means for holding said operated means against free vertical movement to cause said lasting element to wipe the upper heightwise of the last in conjunction with movement of the operated means parallel to the last bottom to carry the upper into position to be secured.

33. In a machine for lasting the sides of shoes, the combination with means for securing a portion of a lasted upper to the rib of an insole, of means positively operated to engage the side of the last adjacent to its bottom, yielding means arranged to form a continuation of the shoe engaging face of said operated means and arranged at an inclination to the shoe bottom, said yielding means being caused to act to upwipe the upper at the side of the shoe during operation of said operated means, and means for holding the yielding means under tension.

34. A lasting machine having, in combination, means for fastening an upper to the rib of an innersole, a lasting member arranged and operated to effect a single upwiping action on the upper prior to each operation of the fastening means and to hold the upper against the upper corner of the edge face of the innersole, and means to hold the upper in the angle between the rib

and margin of the innersole during operation of the fastening means.

35. A machine of the class described having, in combination, means for upwiping 5 a portion of upper in each cycle and for holding the upper against the edge of the innersole, means for working the upper into the angle between the rib and feather of the innersole, and means for fastening the upper 10 to the rib of the innersole.

36. A machine of the class described having, in combination, means for upwiping a portion of a shoe upper against a lipped innersole, means for positioning the lasted

portion against the lip of the innersole, and 15 means for inserting a non-metallic fastening through the lasted portion and the lip of the innersole.

37. A machine of the class described having, in combination, intermittently acting 20 means for upwiping a localized portion of a shoe upper and holding it against the edge of a lipped innersole, and means for inserting an individual fastening through the lasted portion and the lip of the innersole. 25

In testimony whereof I have signed my name to this specification:

FRED N. LA CHAPELLE.
